WRIST CUFF CONSTRUCTION

David E. Weiss, Chicago, Ill., assignor to White-House Manufacturing Co. Inc., South Bend, Ind., a corporation

Application February 28, 1950, Serial No. 146,789

3 Claims. (Cl. 2-270)

1

My invention relates to improvements in wrist cuff constructions for garments.

In certain types of garments, it is desirable to have a wrist cuff construction which intimately hugs the wrists of the wearer. For example, in the case of gowns or frocks worn by surgeons or other operating room personnel, it is particularly essential that the cuffs of the said garments always fit the wrist snugly, since after the gowns have been made sterile, and when worn, the cuffs must hug the wrists so that the surgeon may readily insert his hands into the surgical gloves without necessitating any adjustment on the cuffs, it being readily apparent that any adjustments requiring touching of any part of the surgeon's gown would render it unsterile and unfit for use in surgical procedures. Heretofore, the cuffs of surgeon's frocks were formed of stockinette sections, which functioned in a satisfactory manner when in relatively new condition. However, after the garments were subjected to two or three launderings, the elasticity of the stockinette cuffs usually was destroyed and the cuffs did not properly fit the wrists of the wearer. As a result, the garments became unsuitable for use in surgical procedures and it was the practice in some cases, in order to recondition the garment, to remove the unsatisfactory cuffs and to replace the same with new stockinette sections, while in other cases the sleeves were merely shortened, the cuff portions being cut off and the frocks converted to general purpose garments for use in applications other than in surgical procedures. It is apparent that the relatively short useful life of the stockinette cuffs in relation to that of the garments as a whole, presented a problem of replacement and of maintenance which are important factors in the operating costs of a hospital institution.

Accordingly, it is an object of my invention to provide an improved cuff construction incorporating an elastic band which has a relatively long useful service life, but which may very readily be removed and replaced when deteriorated, thereby materially increasing the useful life of the garment of which it is a part.

Another object of my invention is the provision of a wrist cuff construction which is simple in construction and economical to manufacture.

Other and further objects and advantages of my invention will become apparent from the following description when considered in connection with accompanying drawings in which:

Fig. 1 is a perspective view of an embodiment

of my invention, with certain portions broken away to illustrate details of construction.

Fig. 2 is a fragmentary cross sectional view taken on line 2-2, Fig. 1.

Fig. 3 is a cross sectional view taken on line 3-3 of Fig. 1.

Referring to the drawing, the numeral 10 indicates generally a sleeve terminating in a wrist cuff portion, indicated generally by the numeral 11. In the embodiment illustrated, the sleeve 10 is formed of two sections 12 and 13 joined together by lines of stitching 14 and 16, the cuff portion 11 thereof preferably being integral with the sleeve sections.

Secured to the outer surface of the cuff portion 11, as by lines of stitching 17 and 18, are two panels 19 and 21 in substantially diametrical disposition and spaced from each other. The ends of the said panels, preferably, terminate at points spaced from the seams of the sleeve sections so that sleeve portions 22 and 23 adjacent the seams tend to fold inwardly, as illustrated in Fig. 3, when the sleeve is in collapsed or in partially collapsed condition.

As will be apparent, the panels 19 and 21 form pockets with the cuff portion 11, the said pockets being open at both ends through which is passed an elastic web or band 24. The said web is preferably in one piece, with the ends stitched together along a transverse line 26, to form a closed band adapted to encircle the wrist of the wearer. The band 24 is of smaller circumferential length than that of the cuff portion of the sleeve, so that the said cuff portion is caused to be contracted about the wrist, but will yield to admit the hand of the wearer.

It will be apparent that in my improved cuff construction, should the elasticity of the band 24 become deteriorated as the result of use, the old band may be cut transversely at any point and removed from the receiving pockets, and a new band may be threaded through the pockets and the ends stitched together, transversely thereof. Thus, with a minimum of effort and expense a garment may be placed in a serviceable condition, thereby prolonging the useful life of the garment. If desired, the band 24 may be rotated relative to the cuff portions of the sleeve to dispose the seamed edges under a panel, such as 19 or 21, as illustrated in Fig. 3, to hide the same from view and thereby to present a neater appearance.

In garments using stockinette wrist cuffs, in order to effect replacement, the old cuff portion had to be removed carefully so as not to injure

the sleeve and the new cuff then had to be stitched to the sleeve in a correspondingly careful manner. Such maintenance was time consuming and relatively costly, particularly, in view of the relatively short life of the stockinette cuff. In my improved cuff construction in addition to the increased service life of the elastic band, as compared to that of the stockinette cuff, the manner of replacement of the elastic band is extremely simplified over that of prior cuff constructions employing stockinette cuffs.

While I have illustrated and described a cuff construction having two opposed pockets receiving the elastic band, it is to be understood that it is within the contemplation of my invention to provide a single pocket substantially coextensive with the wrist cuff portion of the sleeve and having a transverse slot or opening through which the elastic band may be threaded through the pocket. Also, instead of two opposed pockets, three or more pockets of shorter length may be circumferentially arranged in spaced relation about the cuff portion of the sleeve.

I claim:

1. In combination with a sleeve formed of two sections joined together along two seams, a panel stitched along the longitudinal edges thereof to each of said sections at the cuff portions of said sections and terminating short of said seams, and an elastic band encircling said cuff portions and received between said panels and said sleeve sections to contract said cuff about the wrist.

2. In combination with a sleeve formed of two sections joined together along two seams, a panel attached to each of said sections at the cuff portion thereof, each of said panels terminating short of said seams and forming with the cuff portion of a sleeve section a pocket open at each transverse end, and an elastic band encircling said cuff portions and received in said pockets between said panels and said cuff portions to contract the cuff portions about the wrist of a wearer.

3. In combination with a sleeve formed of two sections joined together along two seams, a panel attached to each of said sections at the cuff portion thereof, each of said panels forming with the cuff portion of a sleeve section a pocket open at each transverse end, and an elastic band encircling said cuff portions and received in said pockets between said panels and said cuff portions to contract the cuff portions about the wrist of a wearer.
